PASSENGER-OPERATED BOAT

Eugene J. Pieraccioni dit Pierac, Santurce, P. R.,
assignor to Coco Rico Inc., Santurce, P. R., a
corporation of Puerto Rico

Application November 16, 1950, Serial No. 195,998

10 Claims. (Cl. 115—22)

1
This invention relates to a pleasure boat propelled by means operated by at least one of the passengers through a system of pedal actuated paddle means carried by endless belts. More especially the invention relates to a pleasure boat having a pair of floats or hulls of the well known catamaran type.

One important object of the invention is to provide a boat of this character wherein the user may propel the boat with a minimum of effort.

A second important object of this invention is to provide a construction in such a boat as will afford the user the greatest possible comfort and thus fully enjoy operation of the boat.

A third important object of the invention is to provide a novel construction of the hulls of such a boat.

A fourth important object of the invention is to provide novel means for preventing damage to the hulls of such a boat.

A fifth important object of the invention is to provide a novel frame or chassis connecting the hulls of the boat.

A sixth important object of the invention is to provide an improved arrangement of body and means to support the same in such a boat.

A seventh important object of the invention is to provide an improved form of paddle arrangement for the boat whereby loss of the propelling effect of the paddles on the water engaged thereby is prevented.

An eighth important object of the invention is to provide a novel pedal operated driving means for the paddles of such a boat.

Another important object of the invention is to provide a novel and adjustable seat arrangement in such a boat whereby comfort of the users is assured.

With the above and other objects in view, as will be presently apparent, the invention consists in general of certain novel details of construction and combination of parts hereinafter fully described, illustrated in the accompanying drawings, and particularly claimed.

In the drawings like characters of reference indicate like parts in the several views, and

Fig. 1 is a perspective view of the complete boat;

Fig. 2 is a top plan view of the boat with certain parts broken away better to illustrate the invention;

Fig. 3 is an enlarged detail section on the line 3—3 of Fig. 2;

Fig. 4 is a section on the line 4—4 of Fig. 3;

2
Fig. 5 is a section on the line 5—5 of Fig. 4, showing the means for connecting the sections of one of the hulls;

Fig. 6 is a section on line 6—6 of Fig. 2, showing the cushioning means used at the ends of the hulls;

Fig. 7 is a perspective view of one of the boat seats, showing the means for adjusting the seat frame;

10 Fig. 8 is a detailed section on line 8—8 of Fig. 7.

In the construction of the boat in accordance with this invention there is provided a pair of hulls each having a cylindrical tubular middle section 10 which is open at both ends, and a hollow forward section 11 and hollow after section 12 of conoidal form. The major ends of the sections 11 and 12 are of equal diameter with the ends of the section 10. In order to secure the sections of each hull together there is provided for each joint a sleeve 13 which fits snugly in the abutting ends of the sections and is then secured as by the blind riveting 14. At one of its ends the sleeve is provided with a closure 15 dividing the hull member into three compartments which are rendered watertight by packing 16 carried in a circumferential groove formed exteriorly of the sleeve.

The abutting end of each of the sections 11 and 12 is closed by a plate 17 having a peripheral flange 18 formed to fit closely within the section. Mounted on each end of each hull is a hollow bumper or shock absorber 19, preferably formed of stiff but flexible rubber and shaped to form a rounded continuation of the hull shape. Across

30 the bumper 19 extends a transverse brace 20 wherein is screwed the threaded end of a bolt 21 which passes through a suitable opening in the plate 17 and thus secures the bumper firmly in place. Along the bottom of each hull are secured spaced brackets 22 whereto is secured a keel strip 23 which strengthens the hull and assists in preventing damage and possible flooding.

40 The two hulls are connected by tie-bars 24 which extend between the hulls and terminate at their ends in arcuate portions. One arm of each arcuate portion extends upwardly and

45 around the respective hull to lie across the top thereof, this arm being indicated at 25. This arm, for purposes to be presently described has a flat top. Each arcuate portion also has a lower arm 26 which extends downwardly from the respective tie-bar 24 and bears against the in-board side of the hull. Preferably these tie-bars are located at the junction of the middle portion of the hull with the end portion. In order

to secure the arcuate portions to the hulls there is riveted to each of the closing plates 15 an angle member 25' having its ends threaded. These threaded ends project respectively in an upright direction so that they extend through the sleeves 13, the wall of the hull and the members 25. The horizontal leg of the angle 26' extends in an inboard direction through the sleeve 13, wall of the hull and the arcuate portion 26. On the threaded portion of the angle 26' are provided the nuts 27 and 28, the latter being preferably a hand operated nut.

Supported by the tie-bars 24 between the hulls is a body 29. At each side of this body is a running board 30 which rests on the flat portions of the arcuate part of the tie-bar at 25. With this arrangement the hand operated nuts 28 serve to hold the running boards 30 securely in place. The body 29 is provided with a bottom 31 having a belt opening 32 adjacent each end. Between these belt openings there is provided an inverted channel member 33. At the forward end of this channel member is located a forward transverse shaft 34 while at the after end is similarly located an after transverse shaft 35. The forward transverse shaft is supported from the bottom 31 by means of brackets 36 having their lower end slotted as at 37 so that this shaft 34, while prevented from vertical movement has a certain freedom to slide toward and from the adjacent tie-bar. The shaft 35 is similarly supported in brackets 36 but it is not necessary that these brackets should be slotted though this may be done if found desirable. On each of the shafts 34 and 35 is fixedly mounted a set of belt pulleys 39 which are preferably provided with substantially V-shaped peripheral grooves. In these grooves is supported a set of belts 40 which are correspondingly shaped to suit the grooves in the pulleys. The lower run of each belt 40 extends through the channel member 33 at a considerable distance upwardly of the lower edges of this channel member. Each of the shafts 34-35 is journaled in a yoke 41 from which a pull-bar 42 extends to pass through a suitable opening in the adjacent tie-bar. On the threaded end of each pull-rod 42 is mounted a hand nut 43 and by the rotation of this nut in one direction or the other the tension of the belt 40 may be regulated. Extending transversely of the belts and attached to each of said belts is a series of paddles 44, the paddles being preferably evenly spaced along the belts. These paddles 44 have side wings 45 so that the paddles, in moving through water, tend to keep the water from spreading by reason of these side wings. Furthermore, the paddles extend from the belts to such an extent that they substantially divide the space below the lower run of the belt to the edges of the channel 33 into separate pockets from which the water will be held against escape to any appreciable extent. Supported in the body adjacent the forward end thereof is a transverse partition 46 which carries on its after side a set of triangular brackets 47 having at their after ends journal bearings 48. In the journals 48 is a crank-shaft 49 whereon are mounted pedals 50. The pedals for one operator are 180° from each other, while the pedals for the second operator are spaced 90° from the first set of pedals. It is, therefore, clear that there are four pedals on the crankshaft and that an operating force is applied for each quarter revolution of the crankshaft. It may be stated that the crank-shaft or the crankshaft operating forces are at

90° from each other. It may here be noted that this boat is intended for two passengers so that this crankshaft is so formed as to permit rotation by either or both of the passengers.

On the crankshaft is fixed a pair of belt pulleys, termed for convenience driving pulleys 51. On the forward transverse shaft 34 is fixed a pair of driven pulleys 52 and the driving pulleys are operatively connected to the driven pulleys by belts 53. Slidably mounted on the floor 31 is a frame preferably of rod metal and having frames 54 which are connected at their forward upper ends by a transverse member 55 and at their forward lower ends by a transverse member 56. Adjacent each end of the lower member 56 is a sleeve 57 having a slotted adjusting bar 58 extending aft-ward and a hand screw 59 extends through the slot of this member 58 in to the bottom of the body so that when the screw 59 is screwed down the frame will be held against movement. The rear upper ends of the frame sides 54 are connected by a bar 59 braced at its center to the forward bar 55 by a bar 60. The bar 59 is hollow and through this bar extends a rod 61 which supports the lower side members 62 of a frame back having these side members connected to each other by a transverse member 63. Fixed to the lower frame is a plate 64 of substantially segmental form and this plate is provided with a series of openings 65 adjacent its edge wherein is adapted to selectively engage a pin 66 carried by an arm 67 fixed to the frame side 62. By this means the back frame may be rocked to any desired angular relationship with the bottom frame and there held. In order to provide for the comfort of those using this boat the seat proper is formed of a strip of canvas or webbing 68, one end of which is engaged around the transverse member 55 of the seat frame. With this construction the occupants of the boat may lie in a comfortably reclining position and may adjust the seat the most convenient distance from the crankshaft for ease in operating the latter.

The boat may, of course, be provided with any suitable steering gear to operate a rudder 69.

It is now to be observed that this pleasure boat is so constructed and arranged that it may be operated by one or two persons with the greatest of ease, minimum loss of propulsive effort, and in perfectly comfortable position.

While one specific form of the invention has been here shown and described, it is obvious that many minor changes may be made in the form and construction of the present boat without materially departing from the essential features thereof. It is not, therefore, desired to confine the invention to the exact form herein shown and described, but it is wished to include all forms which properly come within the shape claimed.

What is claimed is:

1. In a boat construction, a pair of twin hollow hulls each consisting of a midship section, a forward section, and an after section arranged in axial alignment, sleeves fitting within said sections at the junction of the midship section and the remaining sections and fixedly secured at each side of the respective junction, a closure for one end of each sleeve dividing the hull into separate compartments, and tie-bars extending athwartships between said hulls and secured at their ends thereto, each of said tie-bars having arcuate ends including an arm extending upwardly and across the top of a respective hull

and a second arm extending downwardly of said hull, an angle member secured to the respective closure with one leg extending upwardly and the other laterally in an inboard direction, the legs having ends extending through the walls of the respective sleeve and hull, and through said arms, and securing elements on the projecting portion of said arms.

2. In a boat construction, a pair of twin hollow hulls each consisting of a midship section, a forward section, and an after section arranged in axial alinement, sleeves fitting within said sections at the junction of the midship section and the remaining sections and fixedly secured at each side of the respective junction, a closure for one end of each sleeve dividing the hull into separate compartments, and tie-bars extending athwartships between said hulls and secured at their ends thereto, each of said tie-bars having arcuate ends including an arm extending upwardly and across the top of a respective hull and a second arm extending downwardly of said hull, an angle member secured to the respective closure with one leg extending upwardly and the other laterally in an inboard direction, the legs having projecting ends extending through the walls of the respective sleeve and hull, and through said arms, securing elements on the projecting portion of said arms, a body supported on said tie-bars between said hulls, and running boards extending from the sides of said body over the hulls, the projecting ends of said upright legs extending through said running boards and said securing elements engaging the upper surface of said boards.

3. In a boat construction, a pair of twin hulls, tie-bars extending between said hulls and secured thereto to hold the hulls in parallel relation, a body supported on said tie-bars between said hulls, said body having a bottom provided with a pair of spaced parallel belt openings, an inverted channel member extending between said belt openings, transverse shafts supported in said body, belt pulleys fixed on said shafts, belts extending around said pulleys, the lower run of said belts extending through said channel adjacent the bottom of the body, transversely extending paddles fixed to said belts in spaced relation therealong, yokes in which said transverse shafts are respectively journaled, pull rods each extending through the center of a respective yoke and a respective tie-bar, manually operable securing elements on said pull rods for adjusting the tension of said belts, and means to move said pulleys.

4. In a boat construction, a pair of twin hulls, tie-bars extending between said hulls and secured thereto to hold the hulls in parallel relation, a body supported on said tie-bars between said hulls, said body having a bottom provided with a pair of spaced parallel belt openings, an inverted channel member extending between said belt openings, transverse shafts supported in said body, belt pulleys fixed on said shafts, belts extending around said pulleys, the lower run of said belts extending through said channel adjacent the bottom of the body, transversely extending paddles fixed to said belts in spaced relation therealong, yokes in which said transverse shafts are respectively journaled, pull rods each extending through the center of a respective yoke and a respective tie-bar, manually operable securing elements on said pull rods for adjusting the tension of said belts, upright brackets supported in the forward end of the body and hav-

ing journal bearings at their after ends, a crank shaft journaled in said bearings, pedals on said crank shaft, a driving pulley fixed on said crank shaft, a driven pulley fixed on the forward transverse shaft, and a belt trained around said driving and driven pulleys.

5. In a boat construction, a pair of twin hollow hulls each consisting of a midship section, a forward section and an after section, sleeves fitting within said sections and fixedly secured therein, a closure for one end of each sleeve dividing the hull into separate compartments, and tie-bars extending athwartships between said hulls and secured at their ends thereto, each of said tie-bars having ends including an arm extending upwardly and across the top of a respective hull and a second arm extending downwardly of said hulls, an angle member secured to the respective closure with one leg extending upwardly and the other laterally in an inboard direction, the legs having ends extending through the walls of the respective sleeves and hulls and through said arms, and securing elements on the projecting portions of said arms.

6. In a boat construction, a pair of twin hollow hulls each consisting of a midship section, a forward section and an after section, sleeves fitting within said sections and fixedly secured therein, a closure for one end of each sleeve dividing the hull into separate compartments, tie bars extending athwartship between said hulls and secured at their ends thereto, each of said tie bars having ends including an arm extending upwardly and across the top of a respective hull and a second arm extending downwardly of said hulls, an angle member secured to the respective closure with one leg extending upwardly and the other laterally in an inboard direction, the legs having projecting ends extending through the walls of the respective sleeves and hulls and through said arms, securing elements on the projecting portions of said arms, a body supported on said tie bars, and running boards extending over the hulls, the projecting ends of said upright legs extending through said running boards and said securing elements engaging the upper surface of said boards.

7. In a boat construction, a pair of twin hulls, tie bars extending between said hulls and secured thereto, a body supported on said tie bars, said body having a bottom provided with a pair of spaced parallel belt openings, an inverted channel member extending between said belt openings, transverse shafts supported in said body, belt pulleys fixed on said shafts, belts extending around said pulleys, the lower run of said belts extending through said channel adjacent the bottom of the body, transversely extending paddles fixed to said belts, yokes in which said transverse shafts are respectively journaled, pull rods each extending through the center of a respective yoke and a respective tie bar, manually operable means on said pull rods for adjusting the tension of said belts, and means to move said pulleys.

8. In a boat construction, a pair of twin hulls, tie bars extending between said hulls and secured thereto, a body supported on said tie bars, said body having a bottom provided with a pair of spaced parallel belt openings, an inverted channel member extending between said belt openings, transverse shafts supported in said body, belt pulleys fixed on said shafts, belts extending

around said pulleys, the lower run of said belts extending through said channel adjacent the bottom of the body, transversely extending paddles fixed to said belts, yokes in which said transverse shafts are respectively journaled, pull rods each extending through the center of a respective yoke and a respective tie bar, manually operable means on said pull rods for adjusting the tension of said belts, and means to move said pulleys, upright brackets supported in the forward end 10 of the body and having journal bearings at their after ends, a crankshaft journaled in said bearings, pedals on said crankshafts, and belt and pulley means connecting said crankshaft to said transverse shaft.

9. In a boat construction, a plurality of hulls each consisting of a plurality of sections, sleeves fitting within said sections and fixedly secured therein, a closure for one end of each sleeve dividing the hull into separate compartments, 20 and tie bars extending athwartships between said hulls and secured at their ends thereto, each of said tie bars having ends including an arm extending upwardly and across the top of a respective hull and a second arm extending downwardly of said hulls, an angle member secured to the respective closure with one leg extending upwardly and the other laterally in an inboard direction, the legs having ends extending through the walls of the respective sleeves and hulls and 30 through said arms, and securing elements on the projecting portions of said arms.

10. In a boat construction, a plurality of hulls each consisting of a plurality of sections, sleeves fitting within said sections and fixedly secured therein, a closure for one end of each sleeve dividing the hull into separate compartments, and tie bars extending athwartships between said hulls and secured at their ends thereto, an angle member secured to the respective closure with one leg extending upwardly and the other laterally in an inboard direction, the legs having ends extending through the walls of the respective sleeves and hulls and through said tie bars, and securing elements on said tie bars.
